DESIGN FOR A PLAITED FABRIC

Helen Pisarra, New York, N. Y.

Application November 10, 1941, Serial No. 104,100

Term of patent 3½ years

To all whom it may concern:

Be it known that I, Helen Pisarra, a citizen of the United States of America, residing in New York city, county of Kings, and State of New York, have invented a new, original, and ornamental Design for a Plaited Fabric, of which the following is a specification, reference being had to the accompanying drawing, forming part thereof, wherein,

I claim:

The ornamental design for a plaited fabric, substantially as shown.

HELEN PISARRA.
